(57) **CLAIM**

The ornamental design for a nose-worn air filter, as shown and described.

DESCRIPTION

FIG. 1 is a front elevational view of a nose-worn air filter showing my new design;

FIG. 2 is a rear elevational view thereof;

FIG. 3 is a side view, taken from the left side of FIG. 1, the right side view being a mirror image thereof; and,

FIG. 4 is a top plan view thereof, the bottom plan view being a mirror image thereof.
